CLAIM

The ornamental design for a drip tray portion of an upper-front for domestic water coolers, as shown and described.

DESCRIPTION

FIG. 1 is a front isometric view of a drip tray portion of an upper-front for domestic water coolers, embodying our new design;

FIG. 2 is a top plan view thereof;

FIG. 3 is a rear elevation thereof;

FIG. 4 is a bottom plan view thereof;

FIG. 5 is an end elevation thereof; as viewed from the right in FIG. 1; and,

FIG. 6 is a sectional view thereof taken along line 6—6 of FIG. 3.

The end not shown in FIG. 5 is the mirror image of the end shown therein. Sectional view FIG. 6 is presented to show surface configuration only.
